UNITED STATES PATENT OFFICE.

ALOYSIUS G. BLINCOE, OF BARDSTOWN, KENTUCKY.

MEMORY-JOGGER.

SPECIFICATION forming part of Letters Patent No. 728,358, dated May 19, 1903.

Application filed February 26, 1903. Serial No. 145,040. (No model.)

To all whom it may concern:

Be it known that I, ALOYSIUS G. BLINCOE, a citizen of the United States, residing at Bardstown, in the county of Nelson and State 5 of Kentucky, have invented a new and useful Memory-Jogger, of which the following is a specification.

This invention relates to a device which may be properly designated a "reminding device" or "memory-jogger," the said device comprising in its construction a tab or tablet upon which memoranda of various kinds may be inscribed and afterward erased and means for attaching such tab or tablet to a garment 15 of the wearer where it may be conspicuously worn until the duties to which attention is directed by the memoranda have been performed, when the said tab or tablet may be placed or attached in a position where it will 20 be non-obtrusive and unnoticeable.

The article which forms the subject of my invention is not in any sense a mere memorandum-tablet upon which notes and memoranda for future reference may be inscribed. 25 Its function is perfectly described by the title "memory-jogger," it being specially intended for the use of those who, having a multitude of duties to perform, may require to be specially reminded of some duty of special importance, the desired result being accomplished by exposing the tab or tablet which forms a part of my invention in a position where it will be constantly and conspicuously 30 noticeable and which will serve as a constant reminder until the special duty to which attention is at the time being directed has been performed.

My invention may assume a variety of forms of equal convenience and usefulness. 40 In the present specification I have selected a few of what I deem to be the most convenient and useful modes of construction, as will be hereinafter fully described, and set forth in the claims.

45 In the accompanying drawings, Figure 1 is a perspective view illustrating a preferred form of my invention. Fig. 2 is a sectional view taken longitudinally through the same. Fig. 3 is a view similar to Fig. 2, but showing 50 the attaching means in a different position and showing also in place of a single tab a tablet composed of a plurality of leaves. Fig.

4 is a perspective view illustrating a modification. Fig. 5 is a perspective view showing the base-plate which forms one member of 55 the clamping or attaching device used in this modification. Fig. 6 is a longitudinal sectional view of the device illustrated in said modification. Fig. 7 is a sectional view taken on the line 7 7 in Fig. 6. 60

Corresponding parts in the several figures are indicated by similar numerals of reference.

In the preferred construction of my invention I employ a tab or tablet which may consist of a single leaf, as shown in Figs. 1 and 2, or of a plurality of leaves, as shown in Fig. 3, said leaf or leaves being in either case designated 1.

2 designates a suitably-constructed spring-70 clamp, one of the handle members of which is pivotally connected with the leaf or leaves 1 by means of a riveting device, which may properly consist of an ordinary eyelet, (shown at 3,) said eyelet piercing the handle member 75 4 of the spring-clamp 2, near the end thereof, and likewise engaging the leaf or leaves near their upper edge or edges. It will thus be seen that in either form of construction the clamping device has pivotal connection with the tab 80 or tablet, so that it may be turned to a position in which it shall lie adjacent to said tablet, as shown in Fig. 3, or extend from the upper edge of the same, as will be seen in Fig. 2, whichever may be deemed preferable for the 85 convenient attachment of the device to a garment of the wearer. Usually when the device is not to be exposed conspicuously the clamp is turned to the position shown in Fig. 3, when it may be conveniently connected, 90 for instance, with the rear side of the coat-lapel. When the device is to be conspicuously exposed, its position may be reversed to the front side of the lapel, and it may then be preferable to turn the clamp to the position 95 shown in Fig. 2 in order that the conspicuity of the device may be more pronounced.

The leaf or leaves of the tablet may be made of any suitable material from which pencil-marks may be readily erased, such as suitably-prepared paper, ivory, celluloid, or the like. It will be obvious that when a plurality of leaves are used they will be pivotally connected by the same rivet which connects the 100

leaf or leaves with the clamp or attaching device.

In Figs. 4, 5, 6, and 7 I have illustrated a modified construction of my improved device, 5 in which one of the side members 7 of the spring clamp or clasp is extended and bent, as shown at 8, so as to form a base-plate 9, which may be suitably prepared, as by painting or enameling, to enable it to be written 10 upon and the written marks to be afterward erased. In this form also one or more additional leaves, as 10, may be connected with the base-plate by means of a rivet or eyelet 11, which will enable said leaves to be spread 15 apart from each other for the purpose of inscribing them, as will be readily understood.

It is obvious that my invention is susceptible of a variety of modifications which have not been herein shown or described; but I desire 20 it to be understood that I do not limit myself to the precise forms herein shown, but reserve the right to any changes and modifications within the scope of my invention.

I am aware that tags have been made prior 25 to my invention with attaching devices whereby they may be attached in various positions. I am also aware that memorandum-tablets constructed of leaves pivotally connected, as

by means of a rivet or eyelet, are well known and have long been in public use. I am also 30 aware that spring-clamps have been provided with hooks upon which tags have been detachably supported. Such devices I do not claim.

Having thus described my invention, I 35 claim—

1. In a device of the class described, a spring-clamp, a memorandum-leaf and an eyelet pivotally connecting said leaf and one of the handle members of the spring-clamp 40 which may be thus adjusted to a position adjacent to or extending from the upper edge of said leaf.

2. In a device of the class described, a spring-clamp, a memorandum-leaf and an 45 eyelet pivotally connecting said leaf and one of the handle members of the spring-clamp, one member of the latter being extended to form a base-plate.

In testimony that I claim the foregoing as 50 my own I have hereto affixed my signature in the presence of two witnesses.

ALOYSIUS G. BLINCOE.
